UNITED STATES PATENT OFFICE.

WILLIAM JOHN MILES, OF DENVER, COLORADO.

LEVER-LOCK FOR AUTOMOBILES.

1,166,143.

Specification of Letters Patent. Patented Dec. 28, 1915.

Application filed July 19, 1915. Serial No. 40,610.

To all whom it may concern:

Be it known that I, WILLIAM JOHN MILES, a citizen of the United States, residing in the city and county of Denver and State of Colorado, have invented certain new and useful Improvements in Lever-Locks for Automobiles; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to improvements in means for locking levers against movement when set in a predetermined position. In the specific embodiment of the invention disclosed in the drawing, the invention is intended for use in locking the gear shift lever of an automobile in neutral position in order to prevent the movement of the machine by its own power when the lever is so locked.

20 In other words the object of the invention as disclosed in the drawing is to lock the gear shift lever against movement by an unauthorized person or one not holding a key to the padlock which is employed in securing the parts of the device in the locking position.

25 While the invention is shown applied to a gear shift lever, it must be understood that it is equally applicable to a brake lever, or any other form of lever which it may be desired to lock in a predetermined position of adjustment, to prevent any one except a person having a key to the lock from moving the lever for any purpose.

30 My improved device consists of two parts or members, adapted to embrace the shank of the lever on opposite sides, the two members of the device being interlocked at the base by means of coöoperating hooks and lugs, and secured at the top by a band or ring which holds the upper extremities of the two members against the lateral movement necessary to disengage the interlocked base portions.

35 This device is detachable from the lever, so that when not in use, it may be carried in the tool box of the machine, and is only actually applied to the lever when the owner or user of the machine desires to leave the same.

40 In the drawing I have illustrated the invention as applied to two different styles of

gear shift levers, one style having a ball and socket base, and the other style what may be termed a quadrant base.

Having briefly outlined my improvement, I will proceed to describe the same in detail, reference being made to the accompanying drawing in which is illustrated an embodiment thereof.

45 In this drawing,—Figure 1 is a side elevation of my improved lever lock showing the same in the locking position, the two parts or members being connected by a padlock. Fig. 2 is a side elevation of the device shown on a larger scale, the lock being 50 also applied to a lever. This is a view looking in the direction of arrow 2, Fig. 1, with the padlock removed. Fig. 3 is a similar view with one member or half of the device removed, the securing band at the top being 55 shown in section. Figs. 4 and 5 are sections taken on the lines 4—4 and 5—5 respectively of Fig. 2 looking in the direction of the arrows adjacent said lines. Fig. 6 is a perspective view of the securing band or 60 ring adapted to be applied to the top of the two members constituting the body of the device. Fig. 7 is a fragmentary view of the upper portion of the device showing a slightly modified form of construction so far 65 as the shank of the lever is concerned. Fig. 8 is a side elevation showing the device applied to the gear shift lever operated in connection with a quadrant base. Fig. 9 is a section taken on the line 9—9, Fig. 8, the 70 parts being shown on a larger scale. Fig. 10 is a section taken on the line 10—10, Fig. 11. Fig. 11 is a cross section taken on the line 11—11, Fig. 8.

75 The same reference characters indicate the same parts in all the views.

80 Referring first more particularly to Figs. 1 to 7 inclusive, let the numeral 5 designate each of two approximately twin members which taken together constitute the body of 85 my improved lock. The lower extremity of each of these members is formed semicircular in shape as shown at 6 and hollowed out underneath so that the two parts 6 when 90 taken together form the segment of a sphere, 95 adapted to fit the base 7 of a lever 8 having a shank 9 extending upwardly from the base, the latter being convex in shape to fit the hollowed out part of the base of the locking device. Each of the parts 6 has a 100 laterally projecting lug 10 and a downwardly bent hook 11, the lugs and hooks 105

being oppositely positioned on the two parts 6 and arranged to interlock when the device is assembled. The upper extremity of each member of the lock body consists of a half 5 collar 12, the two collar parts having abutting faces 13 and adapted to be fastened in the assembled relation by means of a securing band or ring 14 which is provided with a depending perforated lug 15 which is 10 adapted to engage a similar lug 16 formed on one of the members 5 near its upper extremity and perforated to register with the perforation of the lug 15 thus forming an opening for the hasp 17 of a padlock 18. 15 Between the parts 6 and 12 of each member of the body of the lock, extends a shank portion 19 which may consist of a half sleeve or a segment of a sleeve, the two parts 19 being hollowed out to fit or approximately fit the shank 9 of the lever to which the device is applied.

As illustrated in the drawing (see Fig. 3), the collar portions 12 are adapted to fit into a circumferential groove 20 formed in the shank of the lever, whereby when the parts 5 are in the assembled relation, longitudinal movement of the device upon the shank of the lever is prevented.

In Fig. 7 instead of forming a groove in the shank of the lever, the latter is provided with a collar 21 forming a shoulder 22 which is engaged by the upper surface of the parts 12, thus preventing the upward movement of the device on the shank of the lever. It will 30 thus be seen that this collar performs substantially the same function as the groove in the other form of structure.

In applying the members 5 to the lever, they are arranged on opposite sides thereof, 40 one member being tilted to form an angle with the other member and so that as the tilted member is brought into the upright position, the hook 11 of each member will interlock with the corresponding lug 10 of 45 the other member, the collar parts 12 at the same time being brought into position to form the complete collar which fits around the shank of the lever being either in engagement with the groove 20 (see Fig. 3), 50 or fitted to the shank of the lever below the shoulder 22 (see Fig. 7). The securing band 14 is then applied to the collar, being supported by virtue of the engagement of its lower surface with the upper extremities of 55 strengthening webs 23 formed on the parts 19 of the members 5. In this event the lug 15 of the band engages the co-operating lug 15 of one of the members 5 so that their perforations register. The hasp 17 of the padlock may then be passed through the opening formed by these two perforations and secured in the locking position, thus making 60 it impossible for any one to remove the device from the lever except a person holding 65 the key to the padlock.

Attention is called to the fact that the parts 6 of the two members 5 have their outer edges formed to flatly fit the surface surrounding the base of the lever, so that when they are in the assembled position as 70 just described, they cannot be tilted in any direction, and as they are fitted to the lever, the latter is secured against movement from the predetermined or neutral position in which it is adjusted.

In the form of construction shown in Figs. 8 to 11 inclusive, my improved lock is shown applied to a lever 8 which is mounted in connection with a quadrant 24, whereby when the lever is in the neutral position (see Fig. 9) the shank 9 is in a central position, and in order to shift it to connect the driving mechanism of the car with the engine or motor, it is necessary to move this shank laterally in one direction or the other whereby it may move in one of the spaces 25 or 26. In this event I construct the base part 6 of each member 5 with two depending projections 27 adapted to respectively enter the spaces 25 and 26 and fill the same to such an extent that the lever cannot be shifted laterally in either direction. With this exception the structure is substantially the same as shown in the other views except that the parts 6 are not semicircular and are not hollowed out at the base as there is no occasion therefor. From this it will be understood that the only desideratum with reference to the formation of the base or lower extremity of the device is that it shall be of such form as to fit the underlying surface in such a manner as to prevent tilting in any direction, in which event the tilting or operating movement of the lever will be prevented.

Hence if the device is applied to a gear shift lever the latter being in the neutral position, the lever cannot be moved to connect the engine with the driving mechanism of the machine. Again if the device is applied to the brake lever, this lever will be locked in the brake setting position or in the position of highest tension, thus preventing the movement of the car. As soon as the person in charge of the machine desires to travel, he unlocks the padlock, removes the same, and lifts the securing band 14 from the collar parts 12, after which the two members 5 of the device may be disconnected from the lever by tilting one member sufficiently to disengage the interlocking lugs and hooks 10 and 11. The device may then be placed in the tool box or other receptacle until it is again needed.

From what has already been explained, it will be understood that my improved lever lock includes a metal shank, jacket, brace or sleeve having a collar or apron extending outwardly, laterally, in either direction from its lower end which is there-

fore expanded. This outwardly projected apron or expanded base constituting the lower end of said shank, sleeve, etc., projects or juts outwardly at such an angle 5 or angles as will conform to the underlying surface, that is the top surface of that part of the car immediately surrounding the lever, whether it be the car floor, the top or any quadrant, quadrant frame, slotted 10 frame or other thing in which the lever of any particular make or kind of car may operate. The upper end of this shank, jacket, brace or sleeve is fitted either under the shoulder or upper edge of a groove cut 15 into the sides of the lever, or under a projecting collar or ring jutting out from the side or sides of any such lever. The upper shoulder or edge of the groove, or the aforesaid out-jutting collar or ring, as the case 20 may be, prevents any perpendicular movement of said brace or sleeve upward along the lever. The surface underlying said apron or expanded brace of said shank, sleeve or brace prevents any perpendicular 25 movement of said shank downwardly or along the lever. Hence, an important feature of this device consists in the construction of said shank, jacket, brace or sleeve whereby it is made immovable perpendicularly, either upward or downward, along 30 the lever, so that any movement of the gear shift lever for instance from the neutral position, or of a brake lever from its position of high tension, is made impossible by the 35 pressure or resistance of the outer portion or edge of said apron, or of the edge or outer portion of said expanded lower end, against its underlying surface; that is, by the resistance of the top surface of the car 40 floor or of any quadrant, slotted frame, etc., against the spread-out lower end of the shank or sleeve. Otherwise expressed, the resistance of the car floor or other underlying surface against the aforesaid expanded 45 lower end of said shank or sleeve prevents any tilting, lateral or horizontal movement of any such lever, and a tilting, lateral or horizontal movement of any such lever is necessary in order to move it from the desired 50 predetermined position, whether such predetermined position be, in the case of a gear shift lever, where the gears are out of mesh, or disengaged, or in the case of a brake lever, where it is at its highest, or a high 55 point of tension.

In the specific embodiment illustrated in the drawing, the device is a metal straight jacket applied to an automobile or motor vehicle lever for the purpose of holding it 60 immovable in any desired, predetermined position. It is evident, however, that any shape for the lower extremity of this device that will prevent the movement of the lever to be locked, from the predetermined position in which it is desired to secure it, is 65

within the scope of the invention as defined by the appended claims.

Having thus described my invention, what I claim is,—

1. In a lever lock the combination with 70 the lever having a stop, of a locking member having means upon one extremity for engaging a support to prevent lateral movement of the lever, and a collar upon its opposite extremity for engaging said stop to 75 prevent movement of the member longitudinally of the lever.

2. The combination with a lever having a stop, of a locking device comprising laterally separable members provided at longitudinally spaced points with lever engaging parts, the said parts at one end of the device being provided with interlocking coöperating 80 elements, and a locking band for encircling the said parts at the other end of the device, said band and one of said members being provided with registering apertured lugs adapted to receive the hasp of a 85 padlock.

3. The combination with a lever, of a 90 locking device composed of two approximately twin members which are separable and interlockingly connected at one end, a band removably encircling the other ends of said members, the band and one of said 95 members being respectively provided with coöperating apertured lugs adapted to receive a padlock hasp.

4. The combination with a lever, of a 100 locking device composed of two approximately twin members which are separable and interlockingly connected at one end, a band removably encircling the other end of 105 said members, the band and one of said members being provided with coöperating apertured lugs adapted to receive a padlock hasp, and means on said locking device for engaging a fixed object to prevent lateral movement of the lock when the locking device is applied.

5. A lever lock comprising two elongated members having concaved faces to engage the opposite sides of said lever, semicircular collar members at one end of said elongated members, strengthening ribs on said elongated members extending to the base of said collar members and forming stops at the base of said collar, a locking band for encircling said collar members, means for connecting said locking band to one of said 115 members, and means at the other end of said elongated members for securing them against separation.

6. A lever lock comprising two elongated members having concaved inner faces and 120 provided at one end with laterally extending base plates, the base plate of each member having a radially extending lug adjacent one of its meeting faces, a laterally extending hook on its other meeting face, the 125 130

hook on each member being designed to engage the lug of the other member for interlockingly connecting said member, and means for clamping the other ends of said 5 members in operative relation.

7. A lock comprising two elongated members having concaved inner faces and provided at one end with laterally extending base plates, the base plate of each member 10 having a radially extending lug adjacent one of its meeting faces, a laterally extending hook on its other meeting face, the hook on each member being adapted to engage the lug of the other member for interlockingly 15 connecting said members, the other end of said elongated member being provided with semicircular collar members overhanging the concaved faces thereof, a band for encircling said collar members, and 20 coöperating means on one of said elongated members and on said band for securing them together.

8. In a lever lock the combination with the lever having a stop, of a locking member whose base is expanded to engage the 25 surface surrounding the lever to be locked, and a collar on said member for engaging said stop to prevent movement of the member longitudinally of the lever.

✓ 30 9. The combination with a lever, of a

locking device composed of two members which are separable and interlockingly connected at one end, said end being expanded and constructed to fit the surface or object by which the lower part of the lever is surrounded, to prevent the device from being tilted from a position corresponding with that of the lever to be secured, means coöperating with the lever to prevent longitudinal movement of the device thereon, and a 35 securing band removably encircling said means for the purpose set forth.

10. The combination with a lever, of a locking device composed of two members which are separable and interlockingly connected at one end, said end being expanded to fit the surrounding surface to prevent 40 tilting of the device, the lever having a stop, a semicircular collar mounted upon the opposite end of each of said members and 45 adapted to engage said stop, and securing means encircling said collar to hold the latter in operative relation.

In testimony whereof I affix my signature in presence of two witnesses.

WILLIAM JOHN MILES.
